UNITED STATES PATENT OFFICE.

JOSEPH F. MUMFORD, OF PHILADELPHIA, PENNSYLVANIA, ASSIGNOR TO ROBERT H. CARNAHAN, OF PHILADELPHIA, PENNSYLVANIA.

VENDING-MACHINE.

1,189,469.

Specification of Letters Patent.

Patented July 4, 1916.

Application filed May 27, 1913. Serial No. 770,150.

To all whom it may concern:

Be it known that I, JOSEPH F. MUMFORD, of Philadelphia, in the county of Philadelphia and State of Pennsylvania, have invented certain new and useful Improvements in Vending-Machines, whereof the following is a specification, reference being had to the accompanying drawings.

The invention relates more particularly to vending machines which are adapted to be attached to the backs of opera chairs or the like, and which are designed for holding small articles, such as gum, chocolates, and similar packages.

15 An object of the invention is to provide a vending device which shall be compact as to the arrangement of parts, and which shall be of simple structure, so that the operating parts will not readily get out of order.

20 A further object of the invention is to provide a vending device wherein a coin receiver may be utilized for turning an operating part by aid of the coin, which operating part is so controlled that a return movement of the receiver first releases the coin and subsequently releases the operating part.

25 A still further object of the invention is to provide a vending device of the above character, wherein the coin-receiving magazine may be turned by the coin, and the movements of the magazine utilized for discharging or vending the articles.

30 A further object of the invention is to provide a device of the above character with a stop mechanism which prevents further movements of the coin receptacle when the packages are all delivered from the vending machine, or when the coin receptacle is substantially full of coins.

35 These and other objects will in part be obvious, and will in part be hereinafter more fully disclosed.

40 In the drawings which show by way of illustration one embodiment of the invention, Figure I, is a front view of the vending machine having my improvements applied thereto. Fig. II, is a rear view of the same, with the back removed to show the inner parts. Fig. III, is a top plan view of the same. Fig. IV, is a sectional view on the line IV, IV, of Fig. II. Fig. V, is a sectional view on the line V, V, of Fig. II. Fig. VI, is a sectional view on the line VI, VI, of Fig. II. Fig. VII, is a sec-

tional view on the line VII, VII, of Fig. II. Fig. VIII, is a sectional view showing the vending arm and the package to be vended in plan. Fig. IX, is a sectional view on the line IX, IX, of Fig. III. Fig. X, is a detail of the lower part of the casing showing the manner of locking the magazine after the last package has been vended. Fig. XI, is a view similar to Fig. VIII, showing in plan the position of the parts corresponding to Fig. X. Fig. XII, is a section on the line XII, XII, of Fig. II. Fig. XIII, is a similar view showing the parts moved and the locking pin securing the magazine to the coin receiver. Fig. XIV, is a sectional view on the line XIV, XIV, of Fig. II. Fig. XV, is a similar view showing the magazine full of coins and the coins actuating the stop lever. Fig. XVI, is a section on the line XVI, XVI, of Fig. II. Fig. XVII, is a view similar to Fig. XVI, showing the magazine held by one of the stop lugs.

The vending machine embodying my improvements consists of a case 1, which is attached to a supporting back 2. As herein shown, a suitable latch 3, is provided for holding the parts locked together, and this latch may be controlled in any desired way for releasing the parts, so as to remove the casing from the back for placing therein a new supply of articles to be vended, or for removing the coins from the coin magazine.

The casing is divided vertically and centrally thereof by a partition 4, which extends from the front of the casing only part way toward the rear side thereof, see Fig. VII. On one side of the casing is a compartment 5, in which the packages to be vended are placed. These packages rest on the lower face of the casing, and suitable guides 6, are provided within the casing for supporting the stack of articles to be vended. A weight 7, is preferably placed on the packages to assist in holding the stack on the supporting plate or base, from which the packages are vended one at a time.

An opening 8, is formed in the casing at the lower end thereof, through which the packages are vended. A door 9, is pivoted to the guides 6, and is adapted to swing so as to close the opening, and is also adapted to be raised to allow the packages to pass through the opening.

On the opposite side of the vertical par-

tion is a coin receptacle or magazine 10. This magazine is cylindrical, and of substantially the same diameter throughout. At the upper end of the coin magazine is a 5 drum 11, around which a coiled spring 12, is placed. One end of this coiled spring is attached to a fixed stop or post 13.

On the outer upper face of the casing is an operating coin receiver 14. This coin 10 receiver is formed with a flat plate lying against the upper face of the case, and said flat plate is slotted as at 15, to receive the coin. Extending laterally from the flat plate is a thumb piece 16. The case is 15 slotted directly underneath the plate, and a lug 17, carried by the coin receiver projects through the slot and engages the other end of the spring 12, which encircles the drum. This spring normally holds the coin 20 receiver with the stop engaging the end of the slot. When the coin receiver is in this position, there is a slot 18, through the casing, which registers with the slot in the coin-receiving plate. Said casing is also 25 provided with a concentric opening, and said plate is formed with a downwardly projecting stem 19, which is slotted as at 20, to permit the coin to pass through as it passes through the slot 15, in the face of the 30 receiver.

The drum 11, at the upper end of the coin magazine is preferably formed so as to engage and turn about said stem as a bearing. This drum is also slotted so that a coin passing 35 through the receiving plate will pass through the slot in the stem and through the slot in the drum when said slot in the drum is in registry with the slot in the case and receiving plate.

40 The coin magazine is formed with a depending portion 21, at one side thereof, to which is attached a plate 22, having a perforation therein and supporting a post which forms a journal box for the lower end 45 of the coin magazine.

A spring 23, surrounding the said post engages the coin magazine at one end, and at its other end is attached to a fixed lug 24, on the case. This spring turns the magazine 50 so as to normally hold the same with the slot in the drum in alinement with the slot in the case, the slot in the stem and the slot in the coin-receiving plate, so that when the coin receiver is in this position a coin 55 may be dropped through the coin-receiving plate and will pass through the stem and the slotted drum until it strikes the ledges 25, and 26, on the coin magazine. These ledges 25, and 26, are formed on inwardly projecting parts of the coin magazine and these parts are also provided with shoulders 27, and 28. When the coin rests on these ledges 60 and the coin receiver is turned in the direction of the arrow indicated in Fig. XII, said coin striking against the shoulders 27, 65

and 28, will cause the magazine to turn with the receiver. The magazine is under tension of the spring 23, which tends to hold the magazine in the position shown in Fig. XII, and, therefore, when the coin receiver 70 is turned by pressure on the thumb piece 16, said coin will be held seated on the ledges and the magazine will be turned, putting said spring 23, under further tension. At the lower end of the magazine or coin receiver 75 I have formed said depending portion with a projecting arm 29. This arm is so positioned that when the coin magazine is turned about its supporting bearings, said arm will engage the lower package in the 80 stack and force the same out through the opening in the case, whereupon it may be withdrawn therefrom. The movement of the package against the pivoted door raises the door and allows the package to be 85 vended. At the lower end of the coin magazine, I have provided a cam rib 30. An arm 31, carried by the pivoted door, is provided with a lug adapted to engage this cam 90 rib, and said cam rib is so proportioned 95 that when the coin magazine is in such position that the delivery arm is withdrawn from the packages, said rib (which has thrown the door to closed position) will prevent the door from being opened to withdraw the packages. When, however, the magazine and receiver are rotated, as above noted, this releases the door, and allows the package to lift the door as the arm presses the package forward. 100

The opening 8, in the face of the casing, through which the package is delivered, is of less length than the package, as clearly shown in Fig. VI. The arm 29, which engages the package is so positioned as to contact with the package at a point near the end of the package which is adjacent the coin magazine, and, as a result, the movement of the arm will cause the package to swing to the diagonal position indicated in 105 Fig. XI, with one corner only projecting from the case. The package is then grasped by the operator of the vending machine and may be pulled from the machine. By this construction, it will be apparent that the fingers of the operator come in contact with the package to be vended only, and, therefore, I have provided a vending device 110 which may be kept in sanitary condition.

A swinging lever 32, is pivoted to the 120 side wall of the case as at 33. The upper end of this lever is provided with a laterally projecting arm 34, which lies in the path of a screw carried by the stem of the coin receiver. The lower end of this lever is 125 formed with a lug 35, adapted to engage stop shoulders 36, carried by the coin magazine. A spring 37, surrounding the pivot stud of the lever engages said lever at one end, and the other end of said spring en- 130

gages a pin 38, on the case, (Fig. V). This spring normally presses the lower end of the lever with the stop lug thereon, into the path of movement of the stop shoulders on 5 the coin magazine.

When the coin receiver is in normal position, so that the slots are in registry, the screw carried by the stem thereof engages the upper end of the lever and moves the 10 same, so as to withdraw the stop lug at the lower end of the lever from the path of the stop shoulders. As soon, however, as the coin receiver is moved to rotate the magazine, the lever is released, and this stop lug 15 moves into the path of travel of the stop shoulders.

If the coin receiver is forced by the operator through pressure on the thumb piece to the extreme movement, the arm 29, will 20 engage the package and move the same to the position indicated in Fig. XI, of the drawings. A releasing of the coin receiver causes the same to be returned to normal position through the action of the spring 12.

25 The first return movement of the receiver to allow the magazine to be rotated in a reverse direction to withdraw the arm 29, from the packages through the action of the spring 23, causes the stop shoulder on the 30 coin magazine to engage the lug on the lever 32, and said magazine will be held from further return movement until the receiver turns the stem 19, so that the screw carried thereby strikes the arm at the upper end of 35 the lever 32, and moves the same so as to withdraw the lug at the lower end of the lever from the stop shoulders. This releases the magazine so that it may be turned to normal position by the spring 23, at the 40 lower end thereof. As soon as the magazine is brought to the first period of rest, wherein the lug on the lever 32, engages the stop shoulder, a further movement of the coin receiver will carry the coin off from the supporting ledges and allow the coin to drop 45 into the receiver.

The lever 52, is provided with a second arm 42, which projects laterally therefrom at a point below its upper end. The magazine 50 is slotted as at 43, and this arm projects into said slot. This arm is also provided with a lug 44, which projects inwardly therefrom. When the coin magazine becomes filled with coins, the upper coins, will 55 engage the lug and prevent the arm from returning to its normal position after the release of the cam receiver. The stop lug 35, at the lower end of lever 32, will therefore be maintained within the path of travel 60 of the stop shoulders on the magazine, and thus prevent the retracting of the magazine and its vending arm, see Fig. XV. This serves as a means for preventing further insertion of coins when the magazine becomes 65 substantially filled, for the reason that when

said magazine is slightly rotated from its full retracted position, the slot in the drum is out of registry with the slots in the case, and receiving plate, thereby bisecting the same, and this prevents the further insertion of coins. 70

The weight resting on the stack of articles to be vended is provided with a pivoted arm 45, which normally rests on the stack of packages. When the last package is 75 moved from beneath the weight, this arm is released and drops behind the vending arm carried by the magazine, so that when the magazine is released and tends to move to retracted position, said arm will strike 80 against the pivoted arm carried by the weight, and prevent the magazine from returning. By this means, I have provided a mechanism which prevents the retracting 85 or turning of the magazine to normal retracted position when there are no further packages in the case to be vended, and this preventing of the magazine from returning to full retracted position, prevents the further insertion of coins. 90

I have, therefore, provided a vending device wherein the magazine for the coins becomes the operating element for moving the arm for vending the packages, and devices are provided which prevent the further insertion of coins when the magazine is full, or the further insertion of coins when the packages are all vended. 95

The coins may be removed from the coin magazine through a pivoted door 38, which 100 closes the lower end of the magazine, and is preferably locked in closed position by a suitable lock.

Having thus described my invention, I 105 claim:

1. A vending device including in combination, an inclosed casing having a delivering opening therein, a coin receiver having a slot therethrough, a coin magazine within the casing, means carried by the magazine 110 for vending the articles through said opening, and devices whereby the coin locks the coin receiver to the magazine for rotating the same.

2. A vending device including in combination, an inclosed casing having a delivering opening therein, a coin receiver having a slot therethrough, a coin magazine within the casing, means carried by the magazine for vending the articles through said opening, devices whereby the coin locks the coin receiver to the magazine for rotating the same, means for temporarily locking the magazine when the package is delivered, and means operated by the releasing of the coin 115 receiver for releasing said magazine. 120

3. A vending device including in combination, an inclosed casing having a delivering opening therethrough, a pivoted door for closing said opening, a coin magazine within 130

- 5 said casing, a coin receiver having a slot there-
in through which a coin may be inserted, de-
vices whereby the coin receiver is locked to
the magazine by the coin, whereby the turn-
ing of the receiver turns the magazine, a
vending arm carried by said magazine, and
means carried by the magazine for locking
the door in closed position when the vend-
ing arm is retracted.
- 10 4. A vending device including in combi-
nation, an inclosed casing having a deliver-
ing opening therethrough, a pivoted door
for closing said opening, a coin magazine
within said casing, a coin receiver having a
15 slot therein through which a coin may be
inserted, devices whereby the coin receiver
is locked to the magazine by the coin, where-
by the turning of the receiver turns the
magazine, a vending arm carried by said
20 magazine, means carried by the magazine
for locking the door in closed position when
the vending arm is retracted, a weight lo-
cated on the packages to be delivered, and
means carried by the weight for preventing
25 the retraction of the vending arm after the
last package is vended.
5. A vending machine including in combi-
nation, an inclosed casing having an open-
ing therein, a vertical partition dividing
30 said casing into a package compartment and
a compartment for a coin magazine, a cylin-
drical coin magazine located in said casing
and adapted to turn about a vertical axis,
a coin receiver having a slot for the coin,
35 a depending slotted stem carried by said
coin receiver and extending into said maga-
zine, said magazine at its upper end having
a drum with a slot adapted to register with
a slot in the coin receiver, lugs carried by
40 the magazine for supporting the coin, and
whereby said magazine may be locked to the
coin receiver, an arm carried at the lower
end of the magazine for engaging and vend-
ing the package from the compartment.
- 45 6. A vending machine including in combi-
nation, an inclosed casing having an open-
ing therein, a vertical partition dividing
50 said casing into a package compartment and
a compartment for a coin magazine, a cy-
lindrical coin magazine located in said cas-
ing and adapted to turn about a vertical axis,
a coin receiver having a slot for the coin,
55 a depending slotted stem carried by said
coin receiver and extending into said
magazine, said magazine at its upper end
having a drum with a slot adapted to regis-
ter with a slot in the coin receiver, lugs car-
ried by the magazine for supporting the
coin, and whereby said magazine may be
60 locked to the coin receiver, an arm carried at
the lower end of the magazine for engaging
and vending the package from the compart-
ment, a spring for normally holding the
magazine turned with the arm retracted, and

65 a spring for returning the coin receiver
when released.

7. A vending machine including in combi-
nation, an inclosing casing having an open-
ing therein, a vertical partition dividing
70 said casing into a package compartment and
a compartment for a coin magazine, a cylin-
drical coin magazine located in said casing
and adapted to turn about a vertical axis,
a coin receiver having a slot for the coin,
75 a depending slotted stem carried by said
coin receiver and extending into said maga-
zine, said magazine at its upper end having
a drum with a slot adapted to register with
a slot in the coin receiver, lugs carried by
80 the magazine for supporting the coin, and
whereby said magazine may be locked to
the coin receiver, an arm carried at the
lower end of the magazine for engaging and
vending the package from the compartment,
85 a lever adapted to engage and lock the mag-
azine with the vending arm moved to full
position for vending the article, and means
carried by the coin receiver for engaging
said lever to release the magazine after the
90 coin has been released from the supporting
lugs.

8. A vending machine including in combi-
nation, an inclosing casing having an open-
ing therein, a vertical partition dividing said
casing into a package compartment and a
95 compartment for a coin magazine, a cylin-
drical coin magazine located in said casing
and adapted to turn about a vertical axis,
a coin receiver having a slot for the coin, a
100 depending slotted stem carried by said coin
receiver and extending into said magazine,
said magazine at its upper end having a
drum with a slot adapted to register with
a slot in the coin receiver, lugs carried by
105 the magazine for supporting the coin, and
whereby said magazine may be locked to the
coin receiver, an arm carried at the lower
end of the magazine for engaging and vend-
ing the package from the compartment, a
110 lever adapted to engage and lock the maga-
zine with the vending arm moved to full
position for vending the article, and means
carried by the coin receiver for engaging
said lever to release the magazine after the
115 coin has been released from the supporting
lugs, said lever having an arm adapted to
be engaged by the coins when the magazine
is full for locking and preventing rotation
of the magazine.

9. A vending device including in combi-
nation, an inclosing casing, a cylindrical
coin magazine located within said casing
and mounted to turn about a vertical axis, a
support for said magazine at the lower end
thereof, a spring engaging said magazine
125 for rotating the same, a vending arm carried
by the lower end of said magazine, a coin
receiver having a slot for the coins, a de-

pending stem carried by said coin receiver and forming a journal for the upper end of the magazine, a drum at the upper end of the magazine having a slot adapted to register with the slot in the coin receiver, a spring engaging said coin receiver for retracting the same, said casing having a slot formed therein in register with the slot in the coin receiver when retracted, and lugs 5 carried by the magazine for engaging the coin and locking the magazine to the coin receiver, whereby said magazine may be rotated by the coin receiver.

10. A vending device including in combination, an inclosing casing, a cylindrical coin magazine located within said casing and mounted to turn about a vertical axis, a support for said magazine at the lower end thereof, a spring engaging said magazine for rotating the same, a vending arm carried by the lower end of said magazine, a coin receiver having a slot for the coins, a depending stem carried by said coin receiver and forming a journal for the upper

end of the magazine, a drum at the upper 25 end of the magazine having a slot adapted to register with the slot in the coin receiver, a spring engaging said coin receiver for retracting the same, said casing having a slot formed therein in register with the slot in 30 the coin receiver when retracted, lugs carried by the magazine for engaging the coin and locking the magazine to the coin receiver, whereby said magazine may be rotated by the coin receiver, a lever pivoted 35 to the casing and having a stop lug adapted to engage a stop shoulder on the magazine, for locking said magazine with the vending arm in forward position, and means carried by the coin receiver for moving said lever 40 to release the magazine.

In testimony whereof, I have hereunto signed my name at Philadelphia, Pennsylvania, this 26th day of May, 1913.

JOSEPH F. MUMFORD.
